CLOTH REEL

George E. B. Welles, San Francisco, Calif.

Application April 22, 1932. Serial No. 606,889

3 Claims. (Cl. 206—50)

My invention relates to cloth reels, especially of that type having a skeleton frame of wood and end caps of metal.

The invention consists in the novel structure of the reel in respect both to its frame and its end caps, as hereinafter fully described.

The object of the invention is to improve said reel, in order to secure certain desirable effects, as will be hereinafter set forth.

10. In the accompanying drawing, the improved cloth reel is shown in its preferred form, though it is to be understood that changes may be made without departing from the spirit of the invention as defined in the claims hereunto appended.

15. In the drawing:—

Fig. 1 is a plan of my improved cloth reel, the paper cover being broken away.

Fig. 2 is a cross section, enlarged, of the reel on a line intermediate its ends.

20. Fig. 3 is a cross section through one end of the reel.

Fig. 4 is a plan view of one of the end caps.

The longitudinal members of the skeleton frame of the reel are the side strips 1 and one or 25 more intervening strips 2 here shown for example, as two, all the strips being preferably made of wood, and assembled in parallel, spaced relation. The side strips 1 are half-round in section, with convex side facing outward, and the intervening strips 2 are rectangular in section. The width of all the strips is equal, so that their edges when assembled lie in even planes.

The ends of the strips are separated by a line of spacer blocks of wood, certain ones of which 35 are wedges adapted to vary the effective length of the spacer line; for example in the form shown the spacers 3 which lie between the side strips and the respective adjacent intervening strips are single blocks, but the spacers 4 between the 40 intervening strips are double, the contacting or meeting ends of the pair being in wedge form, as shown at 5, so that said double blocks 4 have a dual function, namely that of spacing and that of wedging the strips in spaced relation. All the 45 spacers are of such section that they lie flush with the edges of the strips, as shown in Fig. 2.

Supplementing the spacing of the longitudinal strips 1 and 2 at a point or points between the 50 ends are the struts 6. These, for the sake of lightness and strength are preferably made of sheet metal, strengthened by a longitudinal bead 7 and angular ends 8, punched out to form tongues 9, Fig. 2. The struts 6 are fitted flat between the strips 1 and 2, in a plane preferably

midway between the upper and lower edges thereof, the angle ends 8 of the struts bearing against the sides of the strips, and their tongues 9 penetrating them as shown in Fig. 2. Thus the struts are well adapted for easy fitting and ready removal, and when in place they serve effectively to stiffen the frame between its ends; and, by reason of their position, they present no unevenness to the frame surfaces.

10 are the end caps of the reel. These are 65 made of relatively rigid material, preferably metal. They are fully open on one side in order to slip over and embrace the ends of the frame, but on the other side they are only partially open by reason of an inturned flange 11, Figs. 3 and 4, serving the twofold purpose of confining a name plate and exposing to view such inscription as may be on or affixed to said plate. The name plate 12 is a flat strip of wood or relatively stiff cardboard; and the appropriate inscription may 75 be printed directly upon its exposed face or a strip of paper may be laid upon said face and properly inscribed.

By driving in the wedge spacers 4 the ends of the frame are tightened in the caps 10, but upon 80 lifting out said spacers the caps may readily be removed to receive another name plate.

13 is the usual paper cover which envelopes the reel, and as much of the surface of the end caps as may be desired.

85. There are no nails, brads or screws used in the reel. There are no joints or meeting surfaces with edges liable to be or to become uneven or distorted in any part of the reel frame upon which the cloth is wound. The functional surface of the frame is even and smooth throughout; and the paper cover 13 is thus not liable to wrinkle, a condition from which undesirable creasing of the cloth results. There are no small 90 paper strips on the outside subject to wear or liable to be soiled by handling. The whole reel is adapted for easy dismemberment for any purpose, and, conversely, it can be easily assembled, and rendered rigid by the simple expedient of 95 driving in the wedge spacers 4. No preparation such as compression of the frame extremities is necessary to fit them into the end caps, nor need 100 said caps be driven on to said extremities to make a tight fit. Such fit, as above stated, is the simple function of the wedge spacers. The middle zone of the skeleton frame is made rigid by the short, inexpensive metal struts 6, so positioned as not to affect the winding surface of the frame or the paper covering thereof. The reel is light 110

but strong, and its manufacture, both with respect to materials and labor is economical.

I claim:—

- 5 1. In a cloth reel, the combination of a skeleton frame comprising a plurality of strips longitudinally directed in parallel spaced relation, and means at each end for holding said strips in said relation; and additional holding means adapted for application between said strips at points intervening said ends, consisting of struts of sheet metal of less width than the width of the strips, and shaped for compression resistance, said struts having tongues stamped out at each end for penetrating said strips.
- 10 15 2. A cloth reel comprising a frame having

parallel, longitudinal, spaced strips; wedging spacers between and independent of said strips, for increasing their spaced relation; and relatively rigid caps removably fitted upon the strip ends for confining and tightening said strips in 80 their increased spaced relation.

3. A cloth reel comprising a frame having a plurality of parallel, longitudinal, spaced strips; spacers between and independent of the ends of said strips, certain of said spacers being wedges 85 for adjusting the aggregate length of the spacer line and increasing the spaced relation of the strips; and relatively rigid caps removably fitted upon the strip ends and spacer lines.
